UNITED STATES PATENT OFFICE

96,422

DESIGN FOR A CIGARETTE BOX

Edward C. Sloan, Geneva, Ill., assignor to General Electric Company, a corporation of New York

Application May 15, 1935, Serial No. 56,841

Term of patent 14 years

To all whom it may concern:

Be it known that I, Edward C. Sloan, a citizen of the United States, residing at Geneva, in the county of Kane and State of Illinois, have invented a new, original, and ornamental Design for Cigarette Boxes, of which the following is a specification, reference being had to the accompanying drawing, forming part thereof.

The figure is a perspective view of a cigarette box, showing my new design.

The opposite side to that shown in the figure involves a mere duplication of the side shown.

I claim:

The ornamental design for a cigarette box, as shown and described.

In witness whereof, I have hereunto set my hand.

EDWARD C. SLOAN.
